CLAIM

The ornamental design for a charging stand, as shown and described.

DESCRIPTION

FIG. 1 is a perspective view of the charging stand in a deployed configuration showing my new design;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is a perspective view thereof in a retracted configuration;
FIG. 10 is another perspective view thereof in a retracted configuration;
FIG. 11 is a partial enlarged view of portion 11 in FIG. 1;
FIG. 12 is a partial enlarged view of portion 12 in FIG. 1;
and,
FIG. 13 is a partial enlarged view of portion 13 in FIG. 2.
The broken lines in the figures illustrate portions that form no part of the claimed design.
